(57) CLAIM

The ornamental design for a case with bottle cap opener for handheld electronic communications device, substantially as shown and described.

DESCRIPTION

FIG. 1 is a rear view of a case with bottle cap opener for handheld electronic communications device in accordance with the present invention.

FIG. 2 is a front view thereof.

FIG. 3 is a left end view thereof.

FIG. 4 is a right end view thereof.

FIG. 5 is a bottom view thereof.

FIG. 6 is a top view thereof.

FIG. 7 is a front perspective view thereof; and,

FIG. 8 is a rear perspective view thereof.
